(57) **CLAIM**

The ornamental design for a wireless charging station, as shown and described.

DESCRIPTION

FIG. 1 is a front, left, top perspective view of a wireless charging station, showing my new design;
FIG. 2 is a rear, right, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a perspective view of the wireless charging station, shown in a first alternative position; and,
FIG. 10 is a perspective view of the wireless charging station, shown in a second alternative position.

The broken lines in the figures illustrate portions of the wireless charging station that form no part of the claimed design.
